To all whom it may concern:

Be it known that we, John D. Glansburgh, and John Gardiner, of the city of Philadelphia, in the State of Pennsylvania, have invented or produced a new and original Design for Stoves, and we do hereby declare that the following is a full and exact description thereof, reference being had to the accompanying drawings, making a part of this specification, in which,

Fig. 1 is a portion of the bottom plate.

Fig. 2, a portion of top plate of base, with its ornaments.

Fig. 3, a slide plate ornamented.

Fig. 4, an arm ornamented.

Fig. 5, a foot ornamented.

Fig. 6, a portion of top plate of fire chamber, ornamented.

2

Des. 1823

Fig. 7, a portion of extreme top, ornamented.

Fig. 8, a side plate of base, ornamented.

Fig. 9, a door ornamented.

What we claim as our invention, and desire to secure by Letters Patent, is a Design for Stoves as shown and described.
